UNITED STATES PATENT OFFICE.

ALGERNON W. MATTHEWS, OF HAVERHILL, MASSACHUSETTS, ASSIGNOR TO UNITED SHOE MACHINERY COMPANY, OF PATERSON, NEW JERSEY, A CORPORATION OF NEW JERSEY

TOOL-SUPPORT.

1,049,309.

Specification of Letters Patent.

Patented Dec. 31, 1912.

Application filed May 2, 1910. Serial No. 558,788.

To all whom it may concern:

Be it known that I, ALGERNON W. MATTHEWS, a citizen of the United States, residing at Haverhill, in the county of Essex and 5 State of Massachusetts, have invented certain Improvements in Tool-Supports, of which the following description, in connection with the accompanying drawing, is a specification, like reference characters on 10 the drawing indicating like parts in the figure.

This invention relates to a tool support applicable particularly to edge trimming and burnishing machines.

15 The invention is herein shown applied to the shaft of the rand cutter of a heel trimming machine.

It is necessary in trimming or burnishing the sole or heel edges of boots and shoes to 20 use tools of different thicknesses depending upon the character of the work being operated upon; and such machines therefore have provision for supporting a variety of tools of different sizes. In one construction 25 in general use in rotary edge trimming machines, the cutter is supported on a screw-threaded stud that projects from the end of the rotary shaft, the stud being long enough to accommodate the thickest cutter, and the 30 cutter is clamped against the end of the shaft by a screw engaging the threads of the stud. If it is desired to use a thin cutter, it is necessary to place one or more washers or collars back of the cutter to hold it forward in clamping relation to the screw. 35 These washers frequently are misplaced; and, in any event, the operation of changing from one size of tool to another with this arrangement requires considerable time.

40 In order to avoid these disadvantages and to produce a more reliable construction, the present invention purposes providing a tool support that will adjust itself automatically to the thickness of the tool.

45 The nature of this invention will be clearly understood from the following description and the figure of the accompanying drawing, which is a side view partly in section of a tool support embodying this 50 invention.

Referring to the drawing, the shaft 2, which may be mounted and driven in any suitable manner, is provided with a cylin-

drical stud 4 that is concentric with the shaft and projects beyond the end of the latter. 55 An annular recess 6 is formed in the shaft around the stud and extends backwardly from the end of the shaft for a considerable distance. This recess preferably is formed by making the shaft in two sections as indicated in the drawing, one section consisting of a sleeve *a* fitted tightly onto a reduced portion of the other section *b*, thus leaving a recess between the stud 4 and the sleeve. The two sections are turned down to a uniform diameter to adapt the shaft for mounting in suitable bearings. If desired, the recess 6 may be formed in the end of an integral shaft with the aid of a suitable tool. A tubular sleeve 8 fitting snugly onto the 65 stud 4 extends into the recess and forms the direct support for the tool. The sleeve is pressed outwardly with its end normally projecting beyond the end of the stud by a spring 10 interposed between the bottom of 70 the recess and the inner end of the sleeve. In order to prevent the sleeve from turning relative to the shaft it is slotted longitudinally at 12 and a short screw 14 threaded into a radial aperture in the shaft is positioned in the slot. The stud 4 has an axial, 75 screw-threaded hole formed in its end to receive a clamping screw 16.

The cutter 18 is placed on the sleeve 8 with the shield 20 against its outer end and 80 the screw 16 is then turned in with its head bearing against the outer face of the shield until it clamps the cutter firmly against the end of the shaft 2. The shield pressing upon the end of the sleeve forces the latter in 85 against the spring 10 until the cutter strikes the end of the shaft. The drawing shows in full lines the positions of the parts with a thick cutter secured in place. The dotted lines in the figure indicate the positions of 90 the parts when a thin cutter is in place. It will be obvious that in each case the sleeve 95 adjusts itself automatically to the thickness of the tool used.

The screw 16 holds the cutter against the 100 shaft with sufficient friction to prevent its turning on the sleeve, but if desired, the cutter may be splined to the sleeve or secured against turning in any other convenient manner. The distance that the stud 4 105 projects beyond the end of the shaft prefer-

ably is made slightly less than the thickness of the thinnest cutter that is to be used so that sufficient clearance will be left to enable the screw 16 to clamp any cutter against the end of the shaft.

Having described my invention, what I claim as new and desire to secure by Letters Patent of the United States is:—

1. In a machine of the class described, the combination with a shaft, of a tool and a support entering said tool, said support being carried by the shaft and being constructed and arranged to adjust itself automatically to the thickness of the tool.
2. In a machine of the class described, the combination with a shaft, of a tool having a bore formed therethrough, a support entering the bore of said tool, said support being carried by said shaft and being constructed and arranged to adjust itself automatically to the thickness of the tool, and means for securing said tool to the shaft for movement therewith.
3. In a machine of the class described, the combination with a shaft, of a tool, a support for said tool, and means for clamping the tool to the shaft, said support being constructed and mounted to adjust itself automatically to fill the space between said clamping means and said shaft.
4. In a machine of the class described the combination with a shaft, of a tool, a device entering said tool and supporting the same, said device projecting from the end of the shaft and being mounted for movement automatically to adjust itself to the thickness of the tool, and means for clamping said tool against the end of said shaft.
5. In a machine of the class described the combination with a rotary shaft having a screw-threaded stud projecting from its end, of a sleeve axially adjustable on said stud and arranged to telescope within said shaft, a tool positioned on said sleeve and means

cooperating with said stud for clamping said tool against the end of said shaft.

6. In a machine of the class described the combination of a rotary shaft having a screw-threaded stud projecting from its end, said shaft having an annular recess formed in its end surrounding said stud, a sleeve extending into said recess and slideable on said stud, a spring interposed between the bottom of said recess and the inner end of said sleeve and means for preventing said sleeve from turning on said stud.

7. In a machine of the class described the combination of a rotary shaft comprising a section having a concentrically reduced portion and a cylindrical stud projecting concentrically from the end of said portion, and another section of tubular form fitted tightly onto the reduced portion of the first section whereby an annular recess is formed between said tubular section and said stud, said stud having a screw-threaded hole formed in its end, a sleeve slidably mounted on said stud and partially positioned in said recess, a spring interposed between the bottom of said recess and the inner end of said sleeve, said sleeve having a longitudinal slot formed therein, a screw projecting through said slot to prevent the sleeve from turning, a rotary cutter mounted on said sleeve, a shield bearing against the outer end of said cutter and a screw having engagement with the threads of said stud and having its head bearing against said shield to clamp the cutter between the shield and the end of said shaft.

In testimony whereof I have signed my name to this specification in the presence of two subscribing witnesses.

ALGERNON W. MATTHEWS.
